James Thompson Baltimore Maryland

Letters Patent

The Schedule is joined to in these Letters Patent and making part of the same containing a description in the words of the said James Thompson himself of his improvement in the mode of constructing wheels for the use of Rail Road Cars or Locomotive Engines

To all to whom the present shall come. Be it known that I James Thompson of the City and County of Baltimore and State of Maryland have invented a new and useful improvement in the mode of constructing wheels for the use of Rail Road Cars or Locomotive Engines and that the following is a full and exact description thereof.

The rim and spokes of the wheel are to be made of wrought iron. The hub of iron. The spokes may be made in the form of a crop and not quite as wide as the bread of the wheel. varying in thickness according to the weight they are intended to carry. say a quarter to half an inch. A rib should be formed upon each side of said spokes near their meeting of the same thickness as the spokes or more at their bases contracted a little by a taper thence to their outer extremities. Spokes may be also varied both in thickness and width as desired. And for passing a bar say to project five eighths of an inch in width from the spokes on each side may be sufficient. Said spokes may be hollowed in that form. The said ribs should terminate little short of the outer ends of the spokes to fit exactly joint to and come in close upon the interior edge of an internal flange or rib within the rim about half of the rim of the wheel as will be more fully explained hereafter. A wooden pattern may be made to represent the hub and spokes of such wheel as is wanted with the spokes formed as hollowed spokes and also like the rolled wrought iron spokes. Said pattern should be made to stand or open in the center of the hub of the wheel when when moulded in the sand the flange upon one side of the pattern should be a part of the sand. so that when the pat-

87011

rim is withdrawn from the said the iron spokes may be laid into the mould and the cope closed down over them, in this way the hub may be cast upon the spokes. The hub should be sufficiently large to enclose a proper length of the spokes for strength, and yet their inner ends should not be allowed to extend to ^{the} outside to within about one half of an inch of the axle. Thus when the hub is cast it will represent a hub and spokes without a rim, but the ribs on the spokes should not be allowed to extend into ^{the} hub over an eighth of an inch, for this would very nearly divide the hub into two parts, perpendicular through it and thereby makes it unsafe for use. The rim on the exterior may be formed as usual with a flange and cones, or no cones as desired. On the exterior there are to be formed two internal flanges or ribs projecting inwards from the interior of the rim as wide or deep as may be desired, varying according to the objects ^{for} which they are intended to be used. One of said rims or flanges should be formed at the edge of the inner periphery of the outside of the wheel diagonally opposite to the external flange, and it may be made say three quarters of an inch thick at the base tapering to half an inch across the inner edge more or less and one inch and a half wide or deep including the thickness of the rim of the wheel, more or less. This proportion may be proper for a passenger car, and the average thickness of the rim three eighths of an inch. The other rib may be placed midway between this internal and the external flange, or nearer to the external if desired. This rib may not be so deep as the other, it may project within the rim say five eighths of an inch more or less, and must be as thick as the ribs on the spokes, as they are to be fitted to, and to, stand upon the inner periphery of this rib. It may be made in than the ribs on the spokes if desired. It are from nine to twelve spokes for a three to four feet wheel, and then nine to twelve are to be formed a male in the last described internal flange or equivalent from each other of a form and size just to fit close to the outer ends of the spokes, these notches are only to be cut far deep enough to allow the outer ends of the spokes to pass through.

so that when it is expanded by heat, to the extent it will bear without
bursting, there must also be formed notches in the exterior ends of the
ribs, just as deep as the sole of the notch made in the internal rim.
Upon the inner periphery of the rim of said wheel, and also as wide
as the rib itself, so that the notch in the end of the spoke shall occur
upon and fit tight to the rib on the inner periphery of the wheel —
upon the said notches and at the same time the ends of the ribs on
the ends of the spokes are to be formed so exactly to fit upon the inner
periphery of the rib when the tire or rim of the wheel is shrunk by cool-
ing to its natural size, though care must be had to calculate and man-
age the diameter of the spokes and rim, so to agree with each other that when
all the rim shall hug the spokes as tight as they will bear, and at the
same time be the most secure, lasting and safe for use.

Now then it will be seen that the object of these internal ribs, or flanges
is to answer two special purposes. The first is to secure strength and
rigidity in the rim from flexure with but a small quantity of metal,
and the second is to secure the rim to the spokes against
any lateral or other movement without screw bolts, nuts or rivets.

This form of rim will evidently save great weight of iron and
be much stronger than cast iron wheels as usually made. The internal
ribs are a complete substitute for the cast iron rim in point of
strength and firmness, while the rim itself will not be near so lia-
ble to shock, whereby to become loose upon the spokes as the usual
light rim tire when shrunk in the usual way over a solid cast
iron rim, neither could wood within my tire be of any use, no screw
bolts, nuts or rivets to work loose, which requires to be looked after,
and with spokes formed as described their lightness and yet firmness
allow him to make a wheel of less material by one half the usual cast
iron wheel, intended for passenger cars and yet will withstand a blow
upon them twice the force that a cast iron wheel could without breaking.
The wheel of this construction may be made large, the necessary weight
of iron being not to be regarded. On a train this will bear more
and do less of power, wear and tear to the road and cars. The

inner edges of the spokes should be made to fit up tight to the inside of the outer flange or ribs as it will add great additional security to the spokes in the spokes against lateral movement, as the inclination of the peripheries of the wheel is inward or towards each other: hence, inside of the depth of the wheel the spokes beyond the sole of the notches, abundantly secure them to the spokes from any lateral movement.

It is my intention first to roll the iron in a set of dies approximating in a small degree towards the shape of the rim when finished by an estimate based upon a calculation of the necessary weight, and a few experiments the exact weight necessary to form a wheel of a certain diameter by the roller dies may be had to enable us to round up and add to a rough rolled bar before passing it through the finishing dies: in which case the rolling when brought tight together will leave the rim, and so perfect on the surface as to require no turning and yet be made the exact edge that may be wanted. The upper roller of course a form the external flange concave and the face of the face of the wheel and a part of thickness of the rim while the under roller will form the remainder of the thickness of the rim and the internal flanges or ribs the dies in the under roller must be on the outside of its journals while the upper roller must be made so as to be raised by two screws geared together to receive the hoop for rolling and then force the upper roller gradually by the screws as the rollers revolve until they touch each other when the rim will be finished and must then be removed as quick as possible. The hub and spokes must be set into a lathe. The hole bored out to receive the axle. Then placed upon an anvil in a lathe, the ends of the spokes ground off by passing round by an iron wheel in quick motion with a lateral movement to the iron wheel to keep it level or straight upon its surfaces, or before a stone and then a burr cut to be formed as to make a finish to the ends of the ribs and also the notches in the ends of the spokes and after all this prepared the rim must be heated in a coke furnace or should upon the spokes which will then form a wheel perfect, true from the center every way so it may be done in any other as

you may please. I mention it only this morning fully to illustrate
construction of the wheel &c.

that to be claimed as my invention is the internal flanging or webbing with
the consequent bridging of the rim of the wheel and the forward end
of all the spokes so as to connect them and the rim together without
cross bolts or nuts as set forth in the above specification or in any other
specification or mode of construction which effects the same purpose by the
same principles.
